UNITED STATES PATENT OFFICE.

LAUREL LEE BAILEY, OF TERRE HAUTE, INDIANA, ASSIGNOR OF ONE-HALF TO
RUSSELL G. HALL, OF TERRE HAUTE, INDIANA.

WRENCH.

Application filed May 29, 1922. Serial No. 564,427.

To all whom it may concern:

Be it known that I, LAUREL L. BAILEY, a citizen of the United States, residing at Terre Haute, in the county of Vigo and State of Indiana, have invented new and useful Improvements in Wrenches, of which the following is a specification.

This invention relates to a wrench and has for its primary object the construction and arrangements of parts whereby the operation will be such that a more effective grip will be accomplished between the wrench and the object acted upon.

An object of the invention is the novel manner of constructing and arranging the pivoted jaw so that same may be readily moved into locking engagement with the sliding jaw.

A feature of the invention is the quick adjustment of parts and locking thereof during operation of the wrench.

With these and other objects in view the invention will be better understood from the following detailed description taken in connection with the accompanying drawing wherein:

Fig. 1 is a side elevation of the wrench.

Fig. 2 is a longitudinal sectional view.

Fig. 3 is a longitudinal sectional view in engaging position.

Fig. 4 is a section on the line 4—4 of Fig. 3.

Fig. 5 is a detailed view.

Again referring to the drawing illustrating one of the many constructions of my invention the numeral 1 designates a handle member consisting of a body 2 and handle 3. The body 2 is provided with a longitudinally extending groove 4 in which is slidably mounted the shank 5 of the sliding jaw 6. It will be noted the shank is provided with a series of notches 7 and series of gripping teeth 8. A finger 9 is provided for sliding the shank along the groove. The handle member is further provided with depending flanges 10 between which is mount-

ed the pivoted jaw 11 connected to the pivot rivet 12. This pivoted jaw is provided with teeth 13 co-acting with teeth 8 and has a lug 14 adapted to have interchangeable connection with the notches 7.

A trigger 15 projects from the pivoted jaw so as to swing the jaw about its pivot against the action of the spring 16 so that the lug 14 may be forced into engagement with the notches. The pivot rivet 12 is so arranged that pressure on the jaw will tend to hold the lug in rigid engagement with the notches. The spring 16 normally holds the jaw disconnected so that quick adjustment can be accomplished.

From the foregoing description taken in connection with the accompanying drawing it will be apparent that I provide a wrench of simple, inexpensive construction which may be more accurately adjusted and which will be positively locked in adjusted position in a manner to withstand excessive strain.

It is, of course, to be understood that the invention may be constructed in various other manners and the parts associated in different relations and, therefore, I do not desire to be limited in any manner except as set forth in the claim hereunto appended.

Having thus described my invention what I claim is:

A wrench comprising a sliding jaw having a series of notches, a pivoted jaw having a single lug for movement into and out of engagement with said notches, a spring exerting pressure upon the pivoted jaw in a direction to swing same around its pivot and bring the lug out of engagement with the notches and a trigger projecting from the pivoted jaw at a point adjacent said spring so that when pressure is brought to bear upon said trigger the spring will be sprung and the lug thrown into engagement with one of said notches.

In testimony whereof I affix my signature.

LAUREL LEE BAILEY.
